UNITED STATES PATENT OFFICE.

DAVID EDWARD GALLOWAY, OF CLIFTON HEIGHTS, PENNSYLVANIA, ASSIGNOR TO
UNITED SHOE MACHINERY COMPANY, OF PATERSON, NEW JERSEY, A CORPORA-
TION OF NEW JERSEY.

TIP-MEASURING APPARATUS.

1,024,504.

Specification of Letters Patent.

Patented Apr. 30, 1912.

Application filed October 24, 1911. Serial No. 656,416.

To all whom it may concern:

Be it known that I, DAVID EDWARD GALLOWAY, a citizen of the United States, residing at Clifton Heights, Delaware county, Pennsylvania, have invented certain Improvements in Tip-Measuring Apparatus, of which the following description, in connection with the accompanying drawings, is a specification, like reference characters on the drawings indicating like parts in the several figures.

This invention relates to shoe making machinery and particularly to shoe measuring devices adapted for use to assist the workman in ascertaining and recognizing the proper location of certain points or lines of the shoe upper relatively to the last.

The invention is herein shown as embodied in a tip measuring device or apparatus adapted for use on or in connection with a pulling over machine of the type shown in United States Letters Patent 663,777, and the invention will be explained in connection with that machine.

The tip line or the seam that extends transversely across the forepart of the shoe upper and usually unites a toe tip or cap to the shoe vamp, is a prominent line on the shoe and its relation to other portions of the shoe is of great importance in determining the appearance of the shoe. For these reasons much attention is given to the position of the tip line longitudinally of the shoe by which a long or a short tip is determined and uniformity in length for the two shoes of a pair and the pairs of a case is obtained. Also great care must be exercised to insure that the tip seam shall extend at the selected angle to the median line of the shoe. This angle differs in different styles of shoes, being a right angle in some styles and an oblique angle and inclined forwardly toward the outer or the inner side of the shoe in other styles. It is one of the steps of the pulling over operation to locate the tip seam correctly and when that is done carefully it has consumed an appreciable portion of time because it has in practice been done by the use of a graduated scale of peculiar shape which had to be picked up and fitted to the shoe each time it was to be used, and then sometimes dropped while an adjustment of the upper was being made and then applied to the shoe a second time to ascertain if the correction made by the adjust-

ment was adequate to position or to straighten the upper.

An object of the present invention is to provide means which will reduce the time required to be consumed in measuring toe tips in pulling over machines by largely eliminating the handling of the measuring instrument.

A very important feature of this invention consists in the combination with means for operating on a shoe of a tip measurer which is movable into position over the top face of the toe where it discloses to the operator the position of the toe tip seam at the end of the operation of said means on the shoe.

There are certain obvious advantages in measuring over the top face of the toe where the most conspicuous portion of the tip seam is located, and it is also very desirable to have the measurer disclose the position of the tip seam at points separated laterally of the shoe far enough to show the obliquity, if any there be, of the seam to the median line of the shoe. Prior measurers which have been proposed have embodied one or the other of these features but it is a feature of the present invention to provide a tip measurer having both of these important characteristics. This feature of the invention is embodied in a measuring plate that extends across the tip seam on the top face of the toe and through which graduations can be seen at a substantial distance from either side of the median line of the shoe. As shown this plate is made of material through which the tip seam can be observed while covered by the plate. Such transparent material or material which approximates transparency enough to serve this purpose is found in some of the grades of celluloid which I have used to good advantage. The plate may be thin and flexible enough to bend for adapting itself somewhat to the shape of the toe surface over which it is applied.

A further feature of this invention consists in the co-operative relation of the tip measurer to the pulling over means of the illustrated machine. As shown the tip measurer is mounted so that it can swing downwardly and backwardly from an inoperative position to carry the abutment against the toe end and the graduated plate over the tip seam. Retaining means is pro-

vided for causing the measurer to remain automatically in tip position indicating relation to the shoe. This permits the operator to use either or both hands for making adjustments of the upper which may be required to correct the position of the tip seam and enables him, by instant comparison with the gage, to see when the desired adjustment has been secured. A spring is arranged to restore the measurer to upraised position when the retainer is tripped. Such tripping can be done by the hand or it will be done automatically when the machine is restarted for the overdrawing and fastening operations.

The several features of this invention, including certain more important details of construction and principal combinations of parts will appear more fully from the following description and then be pointed out in the claims.

Figure 1 is a side elevation of so much of the machine of said prior patent equipped with this invention as is important to consider in connection with this invention. Fig. 2 is a perspective view of the new tip measurer. Fig. 3 is a fragmentary view showing certain of the upper adjusting mechanism. Fig. 4 is a section in a plane perpendicular to the shoe bottom through that mechanism.

The pulling over machine shown as a whole in said patent comprises toe and side grippers 2 and 4 and operating connections from the power shaft thereto for causing the grippers to seize the upper, updraw it with relation to the shoe bottom rest or sole rest and then come to rest holding the upper under tension. When restarted the grippers are actuated to overdraw the upper into position to be secured upon the shoe bottom, the side clamps 5 seize the shoe and the tackers 6 advance and fasten the upper. The side grippers are connected with rack slides 8, Fig. 3, that engage respectively the upper and lower sides of toothed portions of a shaft 10 from which depends the tip straightening lever 292 of the patent by which the side grippers can be moved in opposite directions longitudinally of the last for adjusting the upper around the last to "straighten" the tip seam or change the angular relation of the seam to the median line of the shoe. The shaft 10 and the rack slides are mounted in boxes 12 that can move together forwardly and backwardly and that have rack teeth on their upper faces, Fig. 2. These rack teeth are engaged by teeth on a foredrawing shaft 15 that has a depending hand lever 91 by which the side grippers can be moved together in the same direction for adjusting the upper forwardly or backwardly. This adjustment positions the tip seam to produce a longer or a shorter tip and the toe

gripper can be further updrawn or be lower in coöperation with the side grippers for this same purpose if desired. There are yielding connections 86, 88, 89 and 90 from the power mechanism to the lever by which automatic foredraw can be obtained, but which do not interfere with manual foredrawing adjustment.

To the machine arranged as above described the new invention is here shown as applied. The frame of the machine pivotally supports in front of the toe gripper a swinging arm 25 that is normally held by a spring 26 in the position indicated in dotted lines. To the lower end of this arm 25 is adjustably secured, by a bolt 28 and vertical and horizontal slots 27, 29, a horizontal arm 30. This arm is forked to provide a slideway for a bar 35 which is normally pressed outward by a spring 36. Upon this bar is pivoted the toe end abutment block comprising the abutment plate 40 and the angular attaching portion 42, said parts being held normally in alignment by springs 43, 43 but permitted slight movement about pivot 44. The lateral edges of a depending portion of abutment plate 40 are embraced by a frame 46 in which is held the transparent or approximately transparent gage plate 45 of celluloid or other suitable material. This gage plate is of suitable size to cover the top face of a shoe and is preferably somewhat flexible so that it will adapt itself to the work as indicated in Fig. 1, where it is bent by engagement with the shoe. On the gage plate is marked a graduated scale as shown by three series of marks, one in the middle of the toe and one at each lateral side of the middle and separated therefrom by unmarked, clear spaces through which the machine operator can get an unobstructed view of the tip seam. Conveniently the graduations into eighths, sixteenths and thirty-seconds of an inch may be marked in different colors to facilitate ready reading of the measurement. The gage plate frame 46 is adjustable up and down on the toe abutment, and for this purpose the portion which embraces the edges of that abutment has an ear in which an adjusting screw 47 is swiveled. This screw is threaded into an ear on the abutment. The frame stiffens the celluloid plate, which is necessarily thin, and said frame has laterally projecting arms 48 by which the operator may engage it for turning the gage plate slightly to one side or the other on pivot 44 if required in measuring shoes on right and left crooked lasts. At its pivotal connection with the machine frame the arm 25 has a hub with a ratchet face on its rear side that is engaged by a pawl 50, Fig. 1, to hold the measuring device or apparatus in its downwardly

swung position and against the action of the spring 26. The pawl has a depending tripper arm 52 standing in the path of the side clamp 5 on the right hand side of the machine, which side clamp carries, for the purpose of operating the tripping device, an inclined plate 54 arranged to effect lifting of the pawl 52 when the side clamp swings into operative shoe supporting position.

10 In the use of the machine equipped with this invention an assembled shoe, comprising a last and innersole and upper materials preferably adjusted relatively and connected together by one or more tacks at the heel end, is presented sole face upwardly against the sole rest of the machine and the upper is positioned between the open jaws of the toe and side grippers 2 and 4. The power is then applied to the cam shaft of the machine and the grippers caused to seize and updraw the upper and also foredraw it if desired, and the machine then comes to rest to permit the operator to inspect the work. He now swings the measuring device down 25 until the toe end abutment 40 is firmly pressed against the shoe as in Fig. 1. The spring 36 yields to allow this firm pressure to be obtained and to maintain it. In this position the pawl 50 locks the measurer.

30 The operator can now look through the gage plate 45 at the tip seam and the graduations disclose to him at a glance both the length of the tip seam and its angular relation to the shoe and he has both his hands free for 35 use in making such adjustments of the upper by the grippers as the measurer shows to be required. The adjustments for length can be made by the foredraw lever 91 and the toe gripper, the updraw lever of which 40 has a handle as in said prior patent. The adjustment for length can also be made by the hand lever 160 by which the last can be moved within the upper as explained in British specification 12,304/03. Adjustment 45 for straightening the tip seam can be made by the tip straightening lever 292. It is to be noted that these adjustments can be made while the operator watches their effect on the upper through the transparent gage 50 plate 45 so that there is no guess work about the adjustment nor any of the cut-and-try practice followed where a hand gage is picked up from the bench and applied after each trial adjustment. The new invention 55 enables the need of adjustment, if any, and its nature and extent to be seen at a glance and the adjustments to be made with no waste of time so that the daily output of the machine and the earnings of the operator are substantially increased by the use of the invention. When the machine is restarted one of the incoming side clamps, which precedes the tackers in order to seize and hold the shoe for the fastening operation, brings the tripper 54 into engagement

with the tripping arm 52 of pawl 50 and lifts that pawl to unlock the measuring device and allow spring 26 to swing it to the dotted line position, Fig. 1, where it is out of the way of the subsequent operations and of the presentation of the next shoe to the machine. The operator can engage the tripping arm 52 and raise the locking pawl 50 at will instead of waiting for the restarting of the machine if that is preferred in any instance.

Having explained the nature of this invention and described a preferred construction embodying the same, I claim as new and desire to secure by Letters Patent of the United States:—

1. A machine of the class described having, in combination, pulling over means and a tip measurer comprising a graduated transparent plate movable relatively to the pulling over means into operative position over the tip seam.

2. A machine of the class described having, in combination, means for working an upper over a last and a tip measurer comprising a transparent graduated plate supported relatively to said means to be applied to the shoe so that the relation of the tip seam to the graduations can be seen through said plate.

3. A machine of the class described, having, in combination, pulling over means, and a tip measurer comprising a toe end abutment and a transparent plate and having graduations, said measurer being supported relatively to said means for movement into operative relation to the forepart of a shoe while the upper is held by the pulling over means.

4. A machine of the class described having, in combination, pulling over means, and a tip measurer mounted for movement in time relation therewith and comprising a toe end abutment and a transparent plate and having graduations relatively to which the position of the tip seam of the pulled upper can be seen through said plate.

5. A machine of the class described having, in combination, pulling over means, and a tip measurer comprising a toe end abutment and a thin flexible transparent celluloid plate on which is marked a graduated scale, and connections on which the measurer is movable into and out of engagement of said abutment and plate respectively with the end and top face of the toe portion of an upper held by the pulling over means.

6. A machine of the class described having, in combination, means for stretching an upper over a last, a tip measurer movable independently of the operation of said means into and out of operative position over the top face of the toe to disclose to the operator the position of the tip seam at the end of the operation of said first mentioned means on

the shoe, and means for automatically moving the measurer in one of said directions.

7. A machine of the class described having, in combination, pulling over means and tip measuring means comprising an end abutment for the last and a connected graduated plate which is movable relatively to the pulling over means into a position determined by the length of the shoe over the 10 tip seam on the top face of the toe.

8. A machine of the class described having, in combination, pulling over means and tip measuring means comprising an end abutment for the last and a connected graduated plate which is movable relatively to the pulling over means into a position determined by the length of the shoe and through 15 which the operator, standing in working relation to the machine, can see the longitudinal and angular relation of the seam to the shoe.

9. A machine of the class described having, in combination, means for pulling over a shoe, a tip measurer mounted for movement at the will of the operator into tip measuring relation to a shoe held by the pulling over means, and means for automatically removing said measurer from position of interference with the subsequent operations of the machine.

10. A machine of the class described having, in combination, means for pulling over a shoe, a tip measurer mounted for movement into tip measuring relation to the top 35 face of the toe, of a shoe held by the pulling over means, automatic means for retaining the measurer, and means operating in time relation with further movements of the pulling over means to free the measurer and 40 withdraw it from the shoe.

11. A machine of the class described having, in combination, means for pulling over a shoe, a tip measurer mounted for movement by the operator into operative position 45 over the toe of a shoe held by the pulling over means, a lock to retain the measurer, a spring tending to restore the measurer to inoperative position and a tripper operated automatically to release the lock 50 when the machine is restarted.

12. A machine of the class described having, in combination, means for pulling over a shoe, a tip measurer mounted for movement at the will of the operator into tip 55 measuring relation to a shoe held by the pulling over means, said measurer comprising an abutment for the end of the shoe and a transparent graduated plate for covering the top face of the toe, means for retaining the measurer over the work and automatic means for removing it.

13. A machine of the class described having, in combination, means for pulling over a shoe, a tip measurer comprising a carrier 60 arm pivoted above the shoe, a gage arm

thereon comprising a toe abutment and a measuring plate to overlie the toe, a lock to hold the measurer in operative position and a spring to restore it to out-of-the-way position when the lock is released.

14. A machine of the class described having, in combination, means for pulling over a shoe arranged to require the presentation of the shoe sole face upwardly thereto, a tip measurer comprising a carrier arm pivoted above the shoe so presented, a gage arm thereon comprising a toe abutment and a measuring plate to overlie the toe, a lock to hold the measurer in operative position, and means which can be tripped manually at will 70 to swing the arm up or will be tripped automatically when the machine is restarted, and means for automatically tripping the measurer.

15. A pulling over machine having, in combination, pulling over means, a tip measurer that can be moved into operative position over the top face of the toe of the shoe and will stay there automatically, means for so retaining the measurer, means for adjusting the upper while the measurer remains in operative position, and means for automatically returning the measurer to inoperative 80 position.

16. A pulling over machine having, in combination, pulling over means, a tip measurer that can be moved into operative position over the top face of the toe of the shoe and will stay there automatically, means for so retaining the measurer, said measurer including a graduated plate through which the machine operator can see the tip seam, means for foredrawing the upper while the effect on the tip seam can be watched, and means for removing the measurer from position of interference with further operations 90 of the machine.

17. In a pulling over machine, pulling over means including a toe gripper, a tip measurer hung in front of the toe gripper and having a depending pivoted arm and a rearwardly extending arm having a toe end abutment and a measuring plate adapted to overlie the top face of the shoe toe.

18. In a pulling over machine, pulling over means including a toe gripper, a tip measurer hung in front of the toe gripper and having a depending pivoted arm and a rearwardly extending arm having a toe end abutment and a measuring plate adapted to overlie the top face of the shoe toe, and automatic means to retain said plate in measuring position.

19. In a pulling over machine, pulling over means including a toe gripper, a tip measurer hung in front of the toe gripper and having a depending pivoted arm and a rearwardly extending arm having a toe end abutment and a measuring plate of transparent material provided with a gradu-

ated scale and adapted to overlie the top face of the toe.

20. A pulling over machine having, in combination, pulling over means and a tip measurer hung in front of the shoe held by the pulling over means to swing down against it and comprising an abutment for engaging the end of the toe and a transparent gage plate for engaging the top face 10 of the shoe forepart.

21. A pulling over machine having, in combination, pulling over means and a tip measurer hung in front of the shoe held by the pulling over means to swing down 15 against it and comprising an abutment for engaging the end of the toe and a transparent gage plate of thin flexible material arranged to engage the top face of the toe and by such engagement to be bent to lie 20 close against and over the tip seam.

22. A pulling over machine having, in combination, pulling over means and a tip measurer hung in front of the shoe held by the pulling over means to swing down 25 against it and comprising an abutment for engaging the end of the toe and a gage plate adapted to extend over the top face of the toe, said plate being formed to permit the tip seam to be seen through it and having 30 a plurality of like graduated scales marked thereon at opposite lateral sides of the middle of the toe.

23. A pulling over machine having, in combination, pulling over means and a tip 35 measurer hung in front of the shoe held by the pulling over means to swing down against it and comprising an abutment for engaging the end of the toe and a transparent gage plate having marked thereon 40 middle and lateral graduated scales spaced apart to allow the tip seam to be seen between them and adapted to indicate respectively the length of the tip and the angular position of the tip seam.

45. 24. A pulling over machine having, in combination, pulling over means, and a tip measurer hung in front of the shoe held by the pulling over means to swing down against it and comprising an abutment for 50 engaging the end of the toe, a gage plate arranged to extend over the top face of the last and means to lock said measurer in its operative position.

55. 25. A pulling over machine having, in combination, pulling over means, and a tip measurer hung in front of the shoe held by the pulling over means to swing down against it and comprising an abutment for 60 engaging the end of the toe, a gage plate arranged to extend over the top face of the last, and a pawl to lock the measurer down, said abutment and gage plate being yieldingly mounted so that yielding engagement of the abutment with the toe end of shoes 65 varying slightly in length or position is

maintained while the measurer is locked by the pawl.

26. A pulling over machine having, in combination, pulling over means and a tip measurer mounted for application to the shoe held by the pulling over means and comprising the swinging arm 25, the carrier block 30 thereon, and the toe abutment and the gage plate slidingly mounted in said block.

27. A pulling over machine having, in combination, pulling over means and a tip measurer mounted for application to the shoe held by the pulling over means and comprising the swinging arm 25, the carrier 80 block thereon, and the toe abutment and the gage plate pivotally connected with said block to turn laterally.

28. A pulling over machine having, in combination, pulling over means and a tip 85 measurer mounted for application to the shoe held by the pulling over means and comprising the swinging arm 25, the carrier block 30 thereon, and the toe abutment and the gage plate slidingly mounted in said 90 block, the pawl 50 to lock the arm and the spring 36 to maintain engagement of the abutment with the work substantially as and for the purpose described.

29. A pulling over machine having, in 95 combination, pulling over means and a tip measurer mounted for application to the shoe held by the pulling over means and comprising the swinging arm 25, the carrier block 30 thereon, and a toe abutment and a 100 gage plate on said arm, said plate being adjustable up and down relatively to said abutment.

30. A pulling over machine having, in combination, pulling over means and a tip 105 measurer mounted for application to the shoe held by the pulling over means and comprising a transparent tip seam gage plate adapted to overlie the top face of the shoe forepart.

31. A pulling over machine having, in combination, pulling over means and a tip measurer mounted for application to the shoe held by the pulling over means and comprising a transparent tip seam gage plate 115 adapted to overlie the top face of the shoe forepart, and having its body portion reinforced and its seam covering portion free and flexible for the purpose described.

32. A pulling over machine having, in 120 combination, pulling over means and a tip measurer mounted for application to the shoe held by the pulling over means and comprising a tip seam gage plate adapted to overlie the top face of the shoe forepart, 125 and provided with a plurality of graduated scales spaced apart and presenting a free space through which the tip seam can be seen.

33. A pulling over machine having, in 130

combination, pulling over means and a tip measurer mounted for application to the shoe held by the pulling over means and comprising a transparent tip seam gage 5 plate adapted to overlie the top face of the shoe forepart and having marked thereon a graduated scale on which different sub-divisions are marked in different colors for the purpose described.

- 10 34. A pulling over machine having, in combination, pulling over means and a tip measurer mounted for application to the shoe held by the pulling over means and comprising the swinging arm 25, the carrier 15 block 30 thereon, and the toe abutment and the gage plate mounted in said block, the locking pawl 50 arranged to hold the arm down and the automatic pawl disengaging means 52, 54.
- 20 35. A pulling over machine having, in combination, pulling over means and a tip measurer mounted for application to the shoe held by the pulling over means and comprising the swinging arm 25, the carrier 25 block 30 thereon, and the toe abutment and the gage plate mounted in said block, means for automatically swinging the arm in one direction and means for locking it at one end of its movement.
- 30 36. A pulling over machine having, in combination, shoe resting means, pulling over means arranged at the side and toe of the shoe, and a gaging device movable into and out of operative position and coöperating 35 with the pulling over means to position the upper properly on the last and comprising a transparent gaging plate through

which the tip seam of the upper can be seen while the gaging device is in operative position.

40 37. In a pulling over machine a tip measurer, means for locking it in operative position, and automatic means to unlock it and to move it out of operative position.

38. A pulling over machine having, in 45 combination, means for pulling an upper over a last, means for measuring the length of the tip, and means for moving the upper at the two ends of the tip lengthwise of the shoe in the same direction to lengthen or 50 shorten the tip.

39. A pulling over machine having provision for adjusting a pulled upper about a last, and tip gaging means coöperating with the upper along the median line of the toe and along other lines spaced from the median line at either side thereof to indicate the length of the tip over the top of the toe and at the sides of the top of the toe.

40. A pulling over machine having provision for adjusting a pulled upper about a last and means for indicating to the operator both the length of the tip over the top of the toe and the angular relation of the tip line of the upper to the longitudinal axis 60 of the last.

65 In testimony whereof I have signed my name to this specification in the presence of two subscribing witnesses.

DAVID EDWARD GALLOWAY.
